UNITED STATES PATENT OFFICE.

SARAH ROBERTS, OF OAKLAND, CALIFORNIA.

DESIGN FOR A SLIPPER.

Application filed August 14, 1922. Serial No. 3,384. Term of patent 3½ years.

To all whom it may concern:

Be it known that I, SARAH ROBERTS, a citizen of the United States, residing at Oakland, in the county of Alameda and State of California, have invented a new, original, and ornamental Design for a Slipper, of which the following is a specification, reference being had to the accompanying drawing, forming part thereof.

The figure is a perspective view of a slipper, showing my new design.

I claim:

The ornamental design for a slipper, as shown.

In testimony whereof I affix my signature.

SARAH ROBERTS.
